MATTRESS FRAME ELEVATING AND LOWERING MECHANISM FOR CRIBS

Walter J. McNabb and William R. Cochrane,
Delhi, Calif.

Application April 11, 1942, Serial No. 438,538

11 Claims. (Cl. 5—11)

This invention relates in general to cribs of the type having a mattress supporting frame arranged for vertical movement or adjustment so as to facilitate tending a child in the crib; and in particular the invention is directed to improvements in the mattress frame elevating mechanism shown in United States Patent No. 2,262,643, dated November 11, 1941.

The principal object of this invention is to provide a mattress frame elevating and lowering mechanism which not only includes manually actuated means to raise and lower the crib, but is arranged with a manually controlled means to apply a braking action against lowering movement of the mattress frame.

A further object of this invention is to provide a mechanism, as above, in which elevating movement of the mattress frame is accomplished from a foot pedal, while lowering movement is accomplished from a hand lever.

An additional object of the invention is to provide an improved pedal actuated mattress frame elevating mechanism which is operative to gradually elevate the mattress frame with a minimum of exertion by the operator.

A further object of the invention is to produce a simple and inexpensive device and yet one which will be exceedingly effective for the purpose for which it is designed.

These objects we accomplish by means of such structure and relative arrangement of parts as will fully appear by a perusal of the following specification and claims.

In the drawings similar characters of reference indicate corresponding parts in the several views:

Figure 1 is a side elevation of the mechanism as mounted below and extending between the front and back panels of a crib.

Figure 2 is a cross section taken on line 2—2 of Fig. 1.

Figure 3 is a fragmentary elevation of the ratchet clutch assembly, showing the clutch disengaged.

Referring now more particularly to the characters of reference on the drawings, the improved mattress frame elevating and lowering mechanism is mounted in connection with a crib of substantially the same construction as shown in the above identified patent, wherein the crib includes end posts 1, side panels 2, end panels 3 and a vertically movable mattress frame 4 suspended at its corners by means of flexible cables 5 connected at one end to ears 6 which project from said corners into vertical pockets 7 in the

end posts. The flexible cables, of which there are a pair at each end, after passing about a pulley arrangement—the lower pulley of which is shown at 8—extend lengthwise of the crib to connection with the operating or winch mechanism. It is to the construction of this operating mechanism that this invention is directed, and such operating mechanism comprises the following:

10 End plates 9 are secured to and depend from the side panels 2 adjacent one end of the crib, and a vertical back plate 10 extends between and connects said end plates in rigid relation, the back plate 10 adjacent its upper edge abutting against and being secured to a frame portion 11 of the end of the crib.

15 A horizontal shaft 12 is journaled in and extends between the end plates 9 adjacent the upper end thereof and in spaced relation in front 20 of the back plate 10; this shaft being additionally supported intermediate its ends by spaced bearing blocks 13. Between the bearing blocks 13 the shaft is fitted with a ratchet clutch assembly which includes a cylindrical clutch body 25 14 fixed in non-rotatable relation on shaft 12, and another cylindrical clutch body 15 rotatably and slidably mounted on shaft 12 in end to end relation with body 14, adjacent ends of bodies 14 and 15 being formed with cooperating ratchet

30 teeth 16. A combination compression and torsion spring 17 surrounds shaft 12 and is connected at one end to the outer end of the body 15 and at the other end is connected to the corresponding bearing block 13.

35 A flexible cable 18 is wound about clutch body 15 in drum-like fashion, being secured at one end to said body. The other end portion of flexible cable 18 extends downwardly to a point below the lower edge of back plate 10 where it is connected with an eye 19 on a foot pedal lever 20 intermediate the ends thereof. The foot pedal lever is normally horizontal, being pivoted at one end as at 21 in connection with an extension 22 depending from one end plate, and extending 45 from such pivotal connection transversely of the crib to a point adjacent and below the opposite end plate. This foot pedal lever is mounted so that its outer or foot-engaging end 23 is horizontally offset from plate 9, which permits the operator to engage the pedal without striking the adjacent portions of the control mechanism. A stop 24 limits upward movement of the foot pedal lever.

45 A ratchet 25, whose teeth oppose the teeth of the ratchet clutch, is fixed on shaft 12 at a

suitable point, a spring-pressed pawl 26 being pivoted on back plate 10 and normally cooperating with ratchet 25 to prevent rotation thereof in a direction which would permit lowering of the mattress frame of the crib. Adjacent the ends of shaft 12 and close to end plates 9 said shaft is fitted with cable drums 27 about which are wound in reverse relation the pairs of flexible cables 5 which extend from opposite ends of the crib; the relation of cables 5 to drums 27 being such that when the mattress frame 4 is elevated the ratchet 25 prevents lowering thereof.

Another horizontal shaft 28 is journaled below shaft 12 and in substantially the same manner, although shaft 28 extends through one of the end plates 9 and therebeyond is fitted with a radial hand lever 29. A brake strap or band 30 is helically wound about cylindrical clutch body 14 intermediate its ends, one end of said brake strap being connected with a length of flexible cable 31 which leads to and winds about a drum 32 fixed on shaft 28 in vertically aligned relation. The other end of brake strap 30 is connected with a length of flexible cable 33 which extends downward to connection with a tension adjustment unit 34 carried by a bracket 35 on the back plate 10.

A radial cam 36 is fixed on shaft 28 in vertical alignment with the outer end portion of clutch body 15, the latter being formed with an annular groove 37 into which the cam 36, upon rotation of shaft 28 in a predetermined direction, is adapted to ride in a direction to effect separation of clutch bodies 14 and 15. Shaft 28 also carries another radial cam 38 which is operative to release pawl 26 from ratchet 25 immediately after the clutch has been disengaged by movement of cam 36.

Operation

The mattress frame 4 is normally in lowered position and to elevate the same the operator places a foot on pedal 23 and depresses the same, which results in rotation of clutch body 14 and, due to the direction which cable 18 is wound, corresponding rotation of clutch body 14 fixed on shaft 12, rotating the latter and winding cables 5 about drum 27. As it requires several strokes of the foot pedal to fully elevate the mattress frame, the operator, after each stroke, releases the foot pedal, which results in clutch body 15 running back or overrunning under the influence of spring 17 and relative to clutch body 14; the ratchet 25 and pawl 27 then—as well as when the mattress frame is in fully elevated position—functioning to prevent lowering of the mattress frame.

To lower the mattress frame, the operator grasps hand lever 29 and swings the same in a direction to successively engage cams 36 and 38 with groove 37 and ratchet 25 respectively, resulting in separation of bodies 14 and 15 of the ratchet clutch assembly, and release of shaft 12 for rotation in a mattress frame lowering direction. The mattress frame, under the weight of the occupant of the crib, immediately begins to lower, but lowered movement is effectively controlled by the brake strap 30, whose tension is then set by the operator by further swinging hand lever 29 in said direction. When the mattress frame reaches its lowered position, the hand lever 29 is released, whereupon all the parts resume their normal positions.

From the foregoing description it will be

readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described our invention, what we claim as new and useful and desire to secure by Letters Patent is:

1. In a crib a vertically movable mattress frame and manually actuated mechanism to raise, and to control lowering movement of said frame; said mechanism including a shaft rotatable in one direction to raise the frame and rotatable in the other direction to permit lowering of the frame, pedal actuated means to rotate the shaft in said one direction, and hand actuated means to apply a braking action against rotation of the shaft in said other direction.
2. In a crib a vertically movable mattress frame and manually actuated mechanism to raise, and to control lowering movement of said frame; said mechanism including a shaft rotatable in one direction to raise the frame and rotatable in the other direction to permit lowering of the frame, pedal actuated means to rotate the shaft in said one direction, a ratchet and pawl unit in part on the shaft normally operative to prevent rotation of the shaft in said other direction, and hand actuated means to release said unit and apply a braking action against rotation of the shaft in said other direction.
3. In a crib a vertically movable mattress frame and manually actuated mechanism to raise, and to control lowering movement of said frame; said mechanism including a shaft rotatable in one direction to raise the frame and rotatable in the other direction to permit lowering of the frame, releasable means cooperating with the shaft normally preventing rotation thereof in said other direction, manually actuated means to rotate the shaft in said one direction, and means including a common, manually actuated control element to release said first named means and apply a braking action against rotation of the shaft in said other direction.
4. In a crib a vertically movable mattress frame and manually actuated mechanism to raise, and to control lowering movement of said frame; said mechanism including a shaft rotatable in one direction to raise the frame and rotatable in the other direction to permit lowering of the frame, a vertically movable pedal mounted beneath said shaft, means between the pedal and shaft to rotate the latter in said one direction upon depression of the pedal, a pawl and ratchet unit in part on the shaft operative to normally but releasably prevent rotation of the shaft in said other direction, a normally released brake unit in part on the shaft, and manually actuated means to release said shaft rotating means and thereafter release said pawl and ratchet unit, and to apply said brake unit whereby to exert a braking action against rotation of the shaft in said other direction.
5. A device as in claim 4 in which said shaft rotating means comprises a ratchet clutch mounted on the shaft and including a drum-like clutch member arranged to overrun in a direction opposite to the holding direction of said pawl and ratchet unit, a flexible element extending between the pedal and said clutch member

and being wound about and secured to the latter so as to rotate the same in a clutch driving direction upon depression of the pedal, and a spring operative to rotate said clutch member in an overrunning direction upon raising of the foot pedal.

6. A device as in claim 4 in which said shaft rotating means comprises a ratchet clutch mounted on the shaft and including a drum-like clutch member arranged to overrun in a direction opposite to the holding direction of said pawl and ratchet unit, a flexible element extending between the pedal and said clutch member and being wound about and secured to the latter so as to rotate the same in a clutch driving direction upon depression of the pedal, and a spring operative to rotate said clutch member in an overrunning direction upon raising of the foot pedal; the ratchet clutch including another drum-like clutch member fixed on the shaft, and said brake unit comprising a brake strap wound about said other clutch, means dead-ending one end of said strap; said hand actuated means including a hand lever mounted exteriorly of the crib, and a pull connection between said lever and the other end of said strap.

7. In a crib a vertically movable mattress frame and manually actuated mechanism to raise, and to control lowering movement of said frame; said mechanism including a shaft rotatable in one direction to raise the frame and rotatable in the other direction to permit lowering of the frame, a ratchet clutch unit mounted on said shaft and operative to overrun in said other direction, a separate opposed ratchet on the shaft, a pawl normally but releasably cooperating with said separate ratchet preventing rotation of the shaft in said other direction, a vertically movable foot pedal mounted below said shaft, connecting means between said pedal and ratchet clutch unit arranged to rotate the latter in a driving direction upon depression of the pedal and to permit said unit to overrun upon raising of the pedal, a spring operative to cause said unit to so overrun, a normally released brake unit on the shaft, and manually actuated means to release said clutch unit and said pawl from the separate ratchet, and to apply the brake unit.

8. In a crib a vertically movable mattress frame and manually actuated mechanism to raise, and to control lowering movement of said frame; said mechanism including a shaft rotatable in one direction to raise the frame and

rotatable in the other direction to permit lowering of the frame, another shaft rotatably mounted substantially parallel to but spaced from said first shaft, a foot pedal mounted for vertical movement beneath said shafts, an exposed hand lever on the outer end of said other shaft, a ratchet clutch unit mounted on said first shaft, a pawl normally but releasably cooperating with said separate ratchet, and means between said first shaft and other shaft operative upon predetermined rotation of the latter to successively disengage said clutch unit and separate ratchet engaging pawl, and to apply a braking action against rotation of said first shaft in said other direction.

9. In a crib a vertically movable mattress frame and manually actuated mechanism to raise, and to control lowering movement of said frame; said mechanism including a shaft rotatable in one direction to raise the frame and rotatable in the other direction to permit lowering of the frame, another shaft rotatably mounted substantially parallel to but spaced from said first shaft, a foot pedal mounted for vertical movement beneath said shafts, an exposed hand lever on the outer end of said other shaft, a ratchet clutch unit mounted on said first shaft, a pawl normally but releasably cooperating with said separate ratchet, and means between said first shaft and other shaft operative upon predetermined rotation of the latter to successively disengage said clutch unit and separate ratchet engaging pawl, and to apply a braking action against rotation of said first shaft in said other direction.

10. A device as in claim 9 in which said clutch unit includes an axially movable body member of cylinder form; said member having an annular groove therein for the reception of the corresponding cam.

11. A device as in claim 9 in which said clutch unit includes a body member fixed on said first shaft, said body member being cylindrical and forming the drum of the brake unit.
